UNITED STATES PATENT OFFICE

162,423

SLED

Charles J. P. Kotchan, Lynbrook, N. Y.

Application March 16, 1950, Serial No. 8,569

Term of patent 7 years

(Cl. D34—15)

To all whom it may concern:

Be it known that I, Charles J. P. Kotchan, a citizen of the United States of America, residing at Lynbrook, county of Nassau, and State of New York, have invented a new, original, and ornamental Design for Sleds, of which the following is a specification, reference being had to the accompanying drawing, forming part thereof, in which:

I claim:

The ornamental design for a sled, as shown.

CHARLES J. P. KOTCHAN.
